UNITED STATES PATENT OFFICE.

JOHN F. KELLY, OF ELMINS, WEST VIRGINIA.

SHOE-DAUBER.

1,340,775.

Specification of Letters Patent.

Patented May 18, 1920.

Application filed November 3, 1917, Serial No. 200,101. Renewed November 10, 1919. Serial No. 337,053.

To all whom it may concern:

Be it known that I, JOHN F. KELLY, a citizen of the United States, residing at Elkins, in the county of Randolph and State 5 of West Virginia, have invented new and useful Improvements in Shoe-Daubers, of which the following is a specification.

This invention relates to blacking daubers especially adapted to be used for applying 10 blacking to shoes and the like and it consists in the novel features hereinafter described and claimed.

An object of the invention is the provision of a dauber of the character stated in which 15 the blacking paste will be delivered to the bristles of the brush for application to the foot wear whereby the same may be polished in the ordinary manner thus obviating the necessity of soiling the hands when applying 20 blacking to the foot wear.

Another object of the invention is the provision of a brush or dauber of the character stated in which the blacking paste or substance is held in a reservoir carried upon 25 the stock of the brush so that the said substance may be dispensed into the bristles of the brush for application thereof to the foot wear, the reservoir being formed from compressible or collapsible metal thus permitting 30 the substance to be ejected therefrom as occasion requires.

In the accompanying drawing:—

Figure 1 is a longitudinal sectional view of the dauber;

Fig. 2 is a top plan view of the same;

Fig. 3 is a transverse sectional view of the same cut on the line 3—3 of Fig. 2.

The dauber comprises a body 1 one end of which may be in the form of a handle. 40 Bunches of bristles 2 are mounted upon the body 1 and the nipple 3 is mounted upon the said body between the bristles 2 as best indicated in Fig. 1 of the drawing. The said nipple 3 is substantially cone-shaped 45 with its larger end connected with the body 1 and its smaller end approximately disposed centrally with relation to the bristle tuft. An L-shaped pipe 4 is mounted upon the top side of the body 1 and one end of 50 the said pipe 4 communicates with the upper end of the nipple 3.

A casing 5 is pivotally connected at one

end with the body 1 and the edge portions of the said casing are adapted to fit snugly along the edges of the body 1 when the said 55 casing is in a closed position upon the body. The casing 5 is provided at its top side with a longitudinally disposed slot 6 and the said casing is provided at its side portion with longitudinally disposed slots 7. 60 A roller 8 is provided at its ends with gudgeons 9 which are received within the slots 7 and the roller is adapted to bear upon a tube 10 which contains the blacking paste. One end of the tube 10 is connected 65 with the pipe 4 and by inserting the finger or thumb through the slot 6, the roller 8 may be moved along the casing 5 whereby the tube 10 is compressed and the contents thereof is forced from the end of the said 70 tube through the pipe 4 and the nipple 3 into the bristles 2 of the brush.

After the tube 10 has been compressed to such an extent as to force all of the paste or blacking therefrom, the free end portion 75 of the casing 5 may be swung in an upward direction with relation to the body 1 whereby the emptied tube may be detached from the pipe 4 and a filled tube substituted in the place thereof.

From the foregoing description taken in conjunction with the accompanying drawing, it will be seen that a dauber of simple and durable structure is provided and that the same may be conveniently used for applying 85 paste to foot wear without waste.

Having described the invention what is claimed is:—

A brush comprising a flat elongated handle member, a casing pivoted at one end 90 thereof to said handle member, being provided at its side with longitudinally disposed slots, the free end of the casing being frictionally engaged with the end of the handle member, a roller having gudgeons 95 received in the slots, a pipe carried by the handle member and housed under the casing and adapted to be connected with a collapsible tube, bristles carried by the handle member and a nipple connected with the 100 pipe and leading into the assemblage of bristles.

In testimony whereof I affix my signature.

JOHN F. KELLY,
